UNITED STATES PATENT OFFICE.

ALBERT E. NEWTON, OF PROVIDENCE, RHODE ISLAND, ASSIGNOR TO RHODE ISLAND LACE WORKS, INC., OF WEST BARRINGTON, RHODE ISLAND, A CORPORATION OF RHODE ISLAND.

DESIGN FOR LACE.

Application filed November 30, 1926. Serial No. 19,884. Term of patent $3\frac{1}{2}$ years.

To all whom it may concern:

Be it known that ALBERT E. NEWTON, a citizen of the United States, residing at Providence, in the county of Providence and State of Rhode Island, has invented a certain new, original, and ornamental Design for Lace, of which the following is a specification, reference being had to the ac-

companying drawing, forming part thereof. The figure is a plan view of a piece of lace embodying my design.

I claim:

The ornamental design for lace substantially as shown.

In testimony whereof I affix my signature.

ALBERT E. NEWTON.
